UNITED STATES PATENT OFFICE.

JOHN L. BROWN, OF PHILADELPHIA, PENNSYLVANIA, ASSIGNOR TO THE POOLEY COMPANY, OF PHILADELPHIA, PENNSYLVANIA, A CORPORATION OF PENNSYLVANIA.

AMPLIFIER.

Application filed May 4, 1926. Serial No. 106,602.

My invention relates to horns or amplifiers and more particularly to a new and improved horn or amplifier adapted to be built into a cabinet, such as may contain a phonograph or radio apparatus.

In connection with horns or amplifiers for phonographs, it is desirable to have the horn or amplifier of as great a length as possible, since within reasonable limits, the greater the length of the horn or amplifier, the more perfect is the reproduced sound.

When a horn or amplifier is built into a cabinet, limitations of space have heretofore dictated the length of the horn or amplifier and desirable length has not been obtainable in cabinets of a practical size.

Now it is the object of my invention to provide a horn or amplifier which may be built into a cabinet and which will require a minimum space, but at the same time, will have a length greatly in excess of the length of similar horns or amplifiers heretofore known. Further objects of my invention are to provide a horn of superior qualities and of a structure capable of variation for the production of desired results.

Having now indicated, in a general way, the nature and purpose of my invention, I will proceed to a detailed description thereof with reference to the accompanying drawings in which there is illustrated a preferred embodiment and in which:

Fig. 1 is a perspective view of an amplifier embodying my invention in association with a portion of a cabinet illustrated diagrammatically.

Fig. 2 is a cross sectional view of the amplifier shown in Fig. 1.

Fig. 3 is a rear view of the amplifier shown in Figs. 1 and 2.

Fig. 4 is a plan view of an amplifier embodying a modification of my invention.

Fig. 5 is a side view of the amplifier shown in Fig. 4.

Fig. 6 is a rear view of the amplifier shown in Figs. 4 and 5.

Referring more particularly to Figs. 1-3, *a* indicates a phonograph cabinet provided with partitions *b*, *b'* between which is formed a chamber for the amplifier to be presently described in detail.

Supported from the partition *b* is a record support or turn-table *c*, adjacent to which is

a tone arm *d* adapted to be connected at one end to a horn or amplifier and which supports at its free end a sound box *e*.

The amplifier comprises a pair of horns having adjacent chambers *f*, *f*, the top, bottom and side walls of which converge from the open forward, or delivery, end of the chambers to an opening at the rear end of the bottoms of the chambers. The convergence of the side walls of the chambers results in the formation of a V-shaped space *g* between the horns.

Beneath the rear end of the horns is positioned a block *h*, having formed within it a pair of conduits *i*, *i* in communication respectively with the openings in the bottoms of the horns and with a common opening *j* formed in the block and opening into the V-shaped space *g*. Supported in the block and in communication with the opening *j* is a conduit *k*, which extends vertically in the space *g* and communicates at its upper end with the tone arm *d*.

The conduit *k* is so formed as to enlarge from its upper to its lower end, while the conduits *i*, *i* starting from the opening *j* are each so formed as to enlarge toward the openings in the bottoms of the chambers *f*, *f* and it will be noted that, while the conduits *i*, *i* at the opening *j* are each approximately one-half of the size of the opening *j*, they are each the same size as the opening *j* at their points of communication with the chambers *f*, *f* of the horns.

It will now be observed that the length of the amplifier from the point of communication of the conduit *k* with tone arm *d* to the delivery ends of chambers *f*, *f* of the horns is very substantial, but that the amplifier as a whole does not occupy any greater space than that occupied by the chambers *f*, *f* of the horns. Further, it will be noted that by virtue of the arrangement of the horns and conduits *k* and *i*, *i* the distribution of sound to the horns is so accomplished as to result in increased volume and more perfect tone at the delivery ends of the chambers.

Referring now to Figures 4-6, the structure of the amplifier is similar to that of Figures 1-3, except that the block *h* is placed on the tops of the chambers *f*, *f* of the horns, the tops of which are provided with openings within which the conduits *i*, *i* in block

h communicate, and that in place of the conduit *k* there is provided a conduit *l*, which is adapted to communicate at one end with the tone arm *d* and which extends downwardly, around and upwardly, in space *g*, into communication with opening *j* in block *h*.

It will be noted that the amplifier shown in Figs. 4-6 is of greatly increased length, but that it does not occupy any additional 10 space over that required for the accommodation of the chambers *f*, *f* of the horns, the increased length being obtained by utilization of the V shaped spaced formed between the horns.

15 While I have described my invention more particularly in relation to a horn or amplifier in association with a phonograph, it will be understood that my invention is equally applicable to horns or amplifiers for use in 20 connection with radio apparatus or with a combination of radio apparatus and phonograph.

Having now fully described my invention, what I claim and desire to protect by Letters 25 Patent is:—

1. An amplifier having a pair of horns each tapering from the front to the rear thereof, there being an inlet opening leading into each of said horns at the rear 30 thereof between the backs and fronts of the horns, a tone arm between the horns at the rear thereof, and having an outlet opening, and a conduit extending from each horn inlet opening to the outlet opening from 35 the tone arm, said conduits lying between the backs and fronts of the horns.

2. An amplifier having a pair of horns each tapering from the front to the rear thereof, there being an inlet opening leading 40 into each of said horns at the rear thereof between the backs and fronts of the horns, a tone arm between the horns at the rear thereof, and having an outlet opening, and a tapered conduit extending from each horn 45 inlet opening to the outlet opening from the tone arm, said conduits lying between the backs and fronts of the horns.

3. An amplifier having a pair of horns each tapering from the front to the rear 50 thereof, there being an inlet opening leading into each of said horns at the rear thereof

between the backs and fronts of the horns, a tapered tone arm between the horns at the rear thereof, and having an outlet opening, and a tapered conduit extending from each horn inlet opening to the outlet opening from the tone arm, said conduits lying between the backs and fronts of the horns.

4. An amplifier having a pair of horns each tapering from the front to the rear thereof, there being an inlet opening leading into each of said horns at the rear thereof between the backs and fronts of the horns, a tone arm between the horns at the rear thereof, and having an outlet opening, and a tapered and reversely curved conduit extending from each horn inlet opening to the outlet opening from the tone arm, said conduits lying between the backs and fronts of the horns.

5. An amplifier having a pair of horns each tapering from the front to the rear thereof, there being an inlet opening leading into each of said horns at the rear thereof between the backs and fronts of the horns, a tapered tone arm between the horns at the rear thereof, and having an outlet opening, and a tapered and reversely curved conduit extending from each horn inlet opening to the outlet opening from the tone arm, said conduits lying between the back and fronts of the horns.

6. An amplifier having a pair of horns each tapering from the front to the rear thereof, there being an inlet opening leading into each of said horns at the rear thereof between the backs and fronts of the horns, a tone arm between the horns at the rear thereof, and having an outlet opening, and a tapered and reversely curved conduit extending from each horn inlet opening to the outlet opening from the tone arm, said conduits lying between the backs and fronts of the horns, the axis of the tone arm being substantially at right angles to the axes of the horns, while the conduits extend substantially at right angles to the axis of the tone arm and the axes of the horns.

In testimony of which invention, I have hereunto set my hand, at Philadelphia, Pennsylvania, on this 1st day of May, 1926.

JOHN L. BROWN.
